UNITED STATES PATENT OFFICE.

JOSEPH E. BATIE, OF DETROIT, MICHIGAN, ASSIGNOR TO KELSEY WHEEL COMPANY, OF DETROIT, MICHIGAN, A CORPORATION OF MICHIGAN.

FELLY-FORMING MACHINE.

1,416,676.

Specification of Letters Patent. Patented May 23, 1922.

Application filed July 11, 1918. Serial No. 244,377.

To all whom it may concern:

Be it known that I, JOSEPH E. BATIE, a citizen of the United States of America, residing at Detroit, in the county of Wayne 5 and State of Michigan, have invented certain new and useful Improvements in Felly-Forming Machines, of which the following is a specification, reference being had therein to the accompanying drawings.

10 The invention relates to the manufacture of wooden fellies for vehicle wheels and has particular reference to a machine for accurately forming the felly sections so that they will fit and will accurately join complementary parts of the wheel. Specifically 15 the invention has reference to a machine for cutting the felly sections to accurate lengths and at the true angles for abutting the complementary sections, but in its broader features 20 the invention is applicable to other machines, such as machines for boring fellies.

In the drawings:

Figure 1 is a plan view of the machine; 25 Figure 2 is a vertical longitudinal section substantially on line 2—2 of Figure 1;

Figure 3 is a sectional elevation on line 3—3 of Figure 1; and

Figure 4 is a view similar to Figure 2 30 showing the parts in a different position of adjustment.

A is a frame, on which is mounted a segmental guide B the inner face of which is a true arc of a radius corresponding to that 35 of the periphery of the wheel felly. C is a vertically reciprocating plunger having a segmental foot D fitting within the guide B and provided with depending fingers E. F is a work-supporting table off from which 40 the fellies are fed by suitable means such as the pusher G into registration with the guide B and foot D, the arrangement being such that the fellies as they are successively fed off from the table will be pressed down

45 by the foot D, the fingers E engaging the inner face at separated points and pressing and conforming the felly to the shape of the guide B. H and H' are cut-off saws which are mounted upon arbors I and I' journalled 50 in a frame J. The plane of the saws is accurately positioned in relation to the guide B and is such that when the felly is depressed said saws will sever the projecting end portions of the felly, cutting it to exactly predetermined length. At the com-

pletion of the operation and after the plunger C is again raised the cut-off felly is disengaged from the guide by a pusher K.

The principle on which the machine operates is that to secure accuracy in the length 60 of the fellies and also end surfaces which will accurately abut the complementary felly sections, it is necessary that the fellies should be of a true arc form during the cutting-off operation. Thus by providing 65 the guide of the proper form, together with means for pressing or clamping the felly to the guide, any irregularity or inaccuracy in the original shape of the felly will be corrected and the cutting-off will be at the right 70 angle as well as the proper length. The fellies when released from the clamp may again distort but when they are finally pressed into the wheel rims they will be 75 conformed to the true circle, in which position their ends will accurately fit and will be subjected to the desired end pressure.

To facilitate the rapid manipulation of the machine, I have provided automatic disengaging and ejecting means for removing 80 the finished felly, which as shown comprises an ejector K slideable over a table L which supports the depressed felly. The ejector K is actuated by the upward movement of the plunger C through the medium of a flexible 85 cable M, one end of which is attached to the plunger and after passing around a pulley O is attached to the cross-bar P extending between the shanks Q and Q' of the ejector. The connection M extends beyond the cross-bar P over a pulley R and has secured to its free end a counterweight S. Thus whenever the plunger is depressed the counterweight will draw the cross-bar P rearward, withdrawing the ejector from the path of 90 the work, and when the plunger is raised the ejector will be actuated in the reverse direction, pushing the work off from the table L.

The fellies may be assembled with the 100 spokes before being operated upon by the machine, so that after the cutting-off operation they are ready for engagement with the rim. Each felly is placed upon the table F between guides T and T', which direct it 105 into proper registration when actuated by the pusher G. A yieldable latch member U supports the center of the felly when pushed off from the table F, and the ends are preferably wedged in between the guides T and 110

T' and inner guides V and V'. This will insure proper engagement of the fingers E with the felly and the accurate conforming of the outer face of the felly to the circular 5 guide B.

What I claim as my invention is:

1. The combination with a guide for conforming a felly to a true arc, of a table upon which the felly is placed and from which it 10 may be fed to said guide, a reciprocating plunger for engaging the felly and forcing the same into conformity to said guide, a saw for cutting off the felly when depressed by said plunger, and an ejector for disengaging the felly.
2. The combination with a work table, of a guide for conforming a felly to a true arc adjacent to said table, means for feeding the felly off from said table into registration 20 with said guide, a plunger for pressing the felly into said guide, and means for cutting off the felly while in engagement with the guide.
3. The combination with a segmental 25 guide for conforming a felly to a true arc, of a plunger for pressing the felly into said guide, a plurality of fingers carried by said plunger for pressing the felly against the guide, and means for cutting off the felly 30 while engaged with the guide.
4. The combination with the segmental guide for conforming a felly to a true arc,

of means for feeding the felly laterally into registration with said guide, a plunger for depressing the felly through said guide, fingers on said plunger for pressing the felly into conformity to said guide while passing therethrough, means for cutting off the felly while in engagement with the guide, and means operated by the retraction of the 40 plunger for ejecting the cut-off felly.

5. The combination with means for conforming a felly section to an arc, of means for cutting off the ends of said felly section in operative relation to said conforming 45 means, and means for ejecting the felly section, actuated by said conforming means.

6. The combination with a guide for conforming a felly section to an arc, of a plunger for pressing the felly into engagement 50 with said guide, and an ejector for disengaging the felly section, said ejector actuated by said plunger.

7. The combination with a guide for conforming a felly section to an arc, of a plunger for pressing the felly section into engagement with said guide, an ejector movable transversely of said guide for disengaging the felly section, and a connection between said ejector and plunger for moving 60 the former from the latter.

In testimony whereof I affix my signature.

JOSEPH E. BATIE.
